Application February 7, 1945, Serial No. 117,808

Term of patent 14 years

(Cl. D74—17)

To all whom it may concern:

Be it known that I, Alex Goldman, a citizen of the United States, residing at Brooklyn, in the county of Kings and State of New York, have invented a new, original, and ornamental Design for a Stylographic Pen, of which the following is a specification, reference being had to the accompanying drawing, forming a part thereof.

I claim:

The ornamental design for a stylographic pen, as shown.

ALEX GOLDMAN.
